FEED MECHANISM FOR LATHES

William F. Groene and Willard L. Groene, Cincinnati, Ohio, assignors to The R. K. Le Blond Machine Tool Company, Cincinnati, Ohio, a corporation of Delaware

Original application October 29, 1937, Serial No. 171,760. Divided and this application January 25, 1939, Serial No. 252,796

1 Claim. (Cl. 74—333)

This is a divisional application of application Serial No. 171,760 filed October 29, 1937 and pertains particularly to a novel feed box arrangement for a lathe. Specifically this invention is directed to a change speed transmission for a lathe feed box including a cone gear and a shiftable gear transmission.

An object is to provide a feed box having a wide range of feed changes and which is compact in design and smooth and quiet in operation.

And a further object is to provide a combined cone gear and shiftable gear transmission having a wide range of speed changes all of which is incorporated on only two shafts in the feed box.

The above features will be described in greater detail and additional features will be pointed out in the following description:

In the drawings:

Figure I is a front elevation partly in section of the feed box on line I—I of Figure III, showing the general arrangement of the transmission and control mechanism.

Figure II is a vertical elevation of the right hand end of the feed box showing the spade handle and indexing and locating plate for positioning the tumbler pinion cylinder.

Figure III is a vertical elevation of the feed box as shown in Figure II but with the indexing and locating plate removed to show the interior arrangement of parts and driving connection from the headstock interior.

Figure IV is a diagrammatic sectional view on the line IV—IV of Figure III showing in detail the arrangement of the gearing and construction of the tumbler operating mechanism.

The novel feed box transmission of our invention is completely enclosed in the feed box 8 and is flooded by lubricant derived from the headstock interior through the opening 4a which matches a similar opening 8a of the feed box 8, Fig. IV. The feed box is mounted on the front of the headstock 4, conveniently located with respect to the operator. The feed box 8 has an accurately machined locating face 210 adapted to abut against an accurately machined locating face 211 provided on the front wall of the headstock 4. Suitable bolts 212 are provided passing through the integral flanges 213 and 214 of the feed box 8 into appropriate tapped holes in the locating face 211 of the headstock 4, to thereby securely hold the box to the headstock and provide a lubricant-tight connection between the faces 210 and 211.

Referring particularly to Figs. III and IV, the drive for the feed box is derived from a gear 129

in the interior of the headstock 4 which drives the gear 215 which is fixed in driving relation on the tumbler cylinder drive shaft 216. The left hand end, Fig. IV, of the shaft 216 is journaled in a suitable anti-friction bearing 217 mounted in the left hand wall 218 of the feed box 8. A nut 219 threaded to the shaft 216 securely holds the inner race of the bearing 217 and driving gear 215 securely against the integral annular flange 220 of the shaft 216. The bearing 217 is held in fixed axial position in the wall 218 by the oil seal ring 221 having the oil seal 222, by holding the outer race of the bearing 217 against the shoulder 223 of the bore 224. The shaft 216 is thus held from axial movement, the bearing 217 being of a character to prevent substantially all axial movement in the shaft. The right hand end of the drive shaft 216 is provided with splines 225 which are slidably supported in a suitable mating splined bore of the tumbler pinion 226, which arrangement provides support for the drive shaft 216 to hold it in proper axial alignment.

The feed box 8 has a very unique construction to provide ease of operation upon the part of the operator. The tumbler cylinder 227 is journaled for axial and pivotal motions in a bore 228 provided in a transverse partition 229 formed integral with the feed box 8 and journaled in a bore 230 in the locating and indexing plate 231, which plate is secured to the right hand end 231a of the feed box 8 by suitable screws 231b. The tumbler pinion 226 is journaled on suitable anti-friction bearings 232 and 233 in the relatively large bore 234 in the tumbler cylinder 227. A locating collar 235 fixed in the bore 234 adjacent the bearing 232 confines the bearings 232 and 233 and the tumbler pinion 226 between the inner face 236 of the bore 234 and the face 237 of the locating collar 235 to thereby prevent substantially all axial movement in the bore 234 of the cylinder 227. The tumbler gear 238 is journaled on the pin 239 fixed in the radially extending bosses 240 and 241 formed integral with the cylinder 227. The radially extending slot 242 between the bosses 240 and 241 extends into the bore 234 and provides means for axially positioning the gear 238 on the pin 239 to thereby maintain driving engagement between the tumbler pinion 226 and the tumbler gear 238 at all times. A clearance bore 243 is provided in the tumbler cylinder 227 for the extended splined end 225 of the draft shaft 216.

The cone gear shaft 244 is journaled in an anti-friction bearing 245 mounted in the left

hand wall 218 of the feed box 8 and in an anti-friction bearing 246 mounted in the locating and indexing plate 231. An intermediate anti-friction bearing 247 for supporting the shaft intermediate the bearings 245 and 246 is mounted in the partition 229 of the feed box 8, the bearing retainer 248 serving to properly adjust the bearings 245 and 246. A cone of gears 249 is fixed to the shaft 244 by means of a suitable key 250 and is secured in proper axial position on the shaft by the lock nut 251 which binds the cone of gears 249 against the shoulder 252 of the shaft 244 adjacent the bearing 247.

We provide a very novel and easily operated control means for causing the tumbler gear 238 to selectively engage the various gears of the cone of gears 249. A manipulating handle 253, of a shape similar to that of a spade handle, has a cylindrical lug 254 snugly fitting in the bore 255 in the right hand end of the tumbler cylinder 227 and secured in place by means of the pin 256. It can thus be seen that the manipulating handle 253 for rocking and axially moving the tumbler cylinder 227 is located substantially on the axis 25 of the cylinder 227.

We provide a unique arrangement for promoting easy selection of tumbler gear positions of cone gear engagement and for securely holding the tumbler gear in selected position. In the manipulating handle 253 is provided a plunger 257, in a diametral bore 258, which has a tapered end 259 adapted to engage mating tapered locating and indexing holes 260 located in an arcuate projection 261 formed integral with the plate 231 and having its radius of curvature of its upper surface 261a substantially concentric with the axis of the cylinder 227. A spring 262 secured in the bore 258 by means of the threaded plug 263, yieldingly urges the plunger 257 radially outward relative to the axis of the tumbler cylinder 227 to thereby hold the tapered end 259 of the plunger 257 in secure engagement with the various tapered holes 260. A trigger 264 pivotally mounted on a pin 265 fixed in the handle 253 and having an integral arm 266 with a rounded end 267 engaging slot 268 in the plunger 257 provides means for withdrawing the plunger from the tapered holes 260 when selecting the various gear changes.

It is to be clearly noted that with the handle 253 gripped with the hand and the plunger 257 withdrawn by pressure of the fingers on the trigger 264 the cylinder may be rotated circumferentially and moved axially to select the desired gear change. It is to be clearly noted that since the handle 253 is located substantially on the axis of the cylinder 227, axial movement of the cylinder by means of the handle causes no binding or cocking of the cylinder in its journals 228 and 230 as is encountered in all of the prior conventional feed change boxes. Another important improvement over prior construction is the location of the point of engagement of the indexing pin 257 with the tapered holes 260 radially far removed from the axis of the cylinder 227 while at the same time having the plunger closely coupled and located relatively near to the tumbler gear 238, not relatively far removed on the end of the manipulating handle as in prior constructions.

In order to facilitate obtaining the proper gear selection, an inclined portion 269 of the arcuate projection 261, facing outward and upward transverse of the lathe, has formed on its upper edge 270 a series of gear change finding notches

corresponding in number and relative position to the gear changes obtainable from the cone of gears 249. On the handle is formed an integral lug 272 having an arcuate indicating blade 273 with a curvature concentric with the axis of the cylinder 227 and of a width to pass with ample clearance through the slots 271 when the cylinder 227 is rotated. A cut-away portion 274 is provided in the indicating blade 273 so that when the handle 253, Fig. II, has been rotated to its extreme clockwise position so that the end 275 of the handle 253 is in contact with the portion 276 of the inclined portion 269, the cut-away portion 274 will then permit the handle and cylinder to be shifted axially. An index plate 277 secured to the inclined portion 269 has columns 278 coinciding with the various notches 271 which show the various threads and feeds obtainable in each of the notches selected.

The operation of shifting the cylinder is relatively simple. The operator grasps the handle 253 and depresses the trigger 264 thereby releasing the plunger 257 from tapered hole 260. The operator then rotates the handle clockwise, Fig. II, until the end 275 of the handle 253 engages the surface 276 of the inclined portion 269 and at the same time removing the indicating blade 273 from an indicating slot 271. Under these conditions the cylinder 227 is free to be moved axially in either direction its maximum travel. The desired thread or feed is selected on the index plate and the handle 253 is moved axially until the blade 273 is positioned over the slot 271 coinciding with the column of the index plate in which the desired thread or feed is found. The operator then merely rotates the cylinder counterclockwise which automatically causes the plunger 257 to engage in the proper tapered hole 260 to properly mesh the tumbler gear 238 with the cone of gears 249. The main advantage of the indicating notches 271 and indicating blade is to enable the operator to quickly and easily determine the proper setting of the tumbler cylinder relative to the index plate, a feature distinctly lacking in all prior constructions. This arrangement also prevents improper meshing of the tumbler gear 238 with the cone of gears 249 and also avoids the necessity of jiggling the cylinder 227 in order to find the proper tapered hole 260 for the locating plunger 257.

In order to provide a wide range of threads and feeds beyond the scope obtainable by means of the cone of gears 249 we provide a series of coarse speed changes in the feed box 8 in addition to the gear changes just described. On the cone gear shaft 244 and integral therewith between the bearings 245 and 247, and adjacent the latter, is formed a twelve-tooth pinion 279. Adjacent the pinion 279 is secured to the shaft 244 a compound gear 280 comprising the small twenty-tooth gear 281 and the larger thirty-tooth gear 282, the compound gear 280 being fixed in driving relation on the shaft 244 by means of the key 283. Between the compound gear 280 and the bearing 245 is journaled the compound gear 284, comprising the large forty-five-tooth gear 285 and the small fifteen-tooth gear 286, having a bushing 287 fixed in its bore and adapted to rotate freely upon the bearing portion 288 of the shaft 244.

Closely associated and parallel with the shaft 244 is provided the output drive shaft 289 of the feed box 8, journaled in an anti-friction bearing 290 mounted in the wall 218 and journaled in an anti-friction bearing 291 mounted in the

partition 229. The bearing retainer 292 having the lubricant seal 293 serves to properly adjust the bearings 290 and 291 to eliminate substantially all axial movement in shaft 289. Formed integral with the shaft 289 adjacent the bearing 290 and between this bearing and the bearing 291 is a fifteen-tooth pinion 294. Adjacent the pinion 294 is rotatively mounted a pinion sleeve 295 having a bearing bushing 296 fixed in its bore 297 adapted to revolve on the bearing portion 298 of the shaft 289. Between the pinion sleeve 295 and the bearing 291 is rotatively mounted the clutch gear 299 having a bearing bushing 300 fixed in its bore 301 adapted to revolve on the bearing portion 302 of the shaft 289. The clutch gear 299 comprises a forty-eight-tooth gear 299a adapted to constant engagement with the twelve-tooth pinion 279 of the shaft 244. Mounted for axial movement on the pinion sleeve 295 is a compound gear 303 adapted to drive the sleeve 295 by means of a key 304 fixed in the sleeve and having sliding engagement in a suitable keyway in the compound gear 303. The compound gear 303 comprises a small thirty-tooth gear 305, a large forty-tooth gear 306, and clutch teeth 307 on the face of the gear 306. When the compound gear 303 is shifted axially to its extreme left position, Fig. IV, the gears 305 and 282 will be brought in driving engagement, when shifted to its intermediate position, as shown in Fig. IV, the gears 306 and 281 will be in driving relation, and when the compound gear 303 is shifted to its extreme right position the clutch teeth 307 will engage mating clutch teeth 308 on the face of the gear 299a, only one of the above combinations being engageable at a time.

Formed integral with the pinion sleeve 295 and adjacent the pinion 294 is a fifteen-tooth pinion 309 of the same dimensions as the pinion 294 of the shaft 289, a portion of the pinion 309 removed from the pinion 294 being adapted to constant driving engagement with the gear 285. On the pinion 294 is mounted a forty-tooth gear 310 having a bore 311 which is an internal gear snugly fitting about the teeth of the pinion 294 but permitting the gear 310 to be shifted axially of the shaft 289. When the gear 310 is shifted fully to the left, as shown in Fig. IV, it will be supported only on the pinion 294 and will then be in driving engagement with the gear 286. When shifted fully to the right, the gear 310 will be disengaged from the gear 286, the internal gear bore 311 of the gear 310 will then engage over the portion of the pinion 309 adjacent the pinion 294 so as to provide a positive driving connection between the shaft 289 and pinion sleeve 295.

In noting the specific example of gear ratios here illustrated we wish to point out the very wide range of speeds obtainable from this arrangement. A series of speed changes, between the cone shaft 244 and feed output shaft 289, from one to thirty-two-to-one are obtained as follows: With the gears 312 shifted to the right so that the sleeve 295 is connected in direct driving relation to the output shaft 289, engagement of gears 282 and 305 provides a 1-to-1 ratio; engagement of gears 281 and 306 provides a 2-to-1 ratio; and engagement of the clutches 307 and 308 provides a 4-to-1 ratio. With the gear 310 shifted to the left engaging the gear 306 an 8-to-1 ratio is provided from the sleeve 295 and the output shaft 289 through the gear 309 and driving gear 285 and gear 286 driving gear 294;

so that engagement of gear 282 and 305 provides an 8-to-1 ratio; engagement of gears 281 and 306 provides a ratio of 16-to-1; and engagement of the clutches 307 and 308 provides a 32-to-1 ratio. Intermediate ratios between the six major ratios just noted are obtained from the cone of gears 249 cooperating with the tumbler gear 238 as already described.

While we have cited specific gear ratios in this illustration to more clearly give some idea of the wide range of feeds and threads obtainable from this novel, compact feed box transmission, it is to be clearly understood that we are in no way limited in the scope of our invention to the specific example herein disclosed.

The means for selecting the six major speed changes of the feed box transmission noted above comprises a control handle 312, Figs. I, II, III, V and VI, fixed to the transversely located rock shaft 313 journaled in the front wall 314 and rear wall 315 of the feed box 8. On the shaft 313 is fixed a gear 316 between the wall 315 and 314 and adjacent the latter wall 314 which is adapted to engage a rack 317 formed on the top of the longitudinally located shifter rod 318, the rod 318 being mounted and axially slidable in the wall 218, in the partition 229, and in a base 319 formed integral with the wall 231a of the feed box. Fixed to the rod 318 intermediate the wall 218 and partition 229 is a shifter yoke 320 adapted to contact the compound gear 303 in the annular slot 312. Thus, by moving the handle 312 to the right or left the rod 318 through the rack 317 and gear 316 will be moved axially and by means of the shifter yoke 320 the compound gear 303 can be easily shifted to the respective positions already discussed. Indicating letters A, B, and C, shown in Fig. VI, are provided to show the position selected relative to the feeds and threads obtained as shown on the index plate 40 277. These positions are shown in column 321 of the index plate 277. A detent arrangement comprising the plunger 322 urged against the rod 318 by a spring 323 in a suitable bore 324 in the boss 319 engages in the notches 325 when proper shifted positions are selected.

In a like manner the gear 310 is shifted by means of the handle 326, located directly under the handle 312, through the transverse rod 327, the gear 328, the rack 329 on the rod 330, and the shifter yoke 331 fixed to the shaft and engaging around the gear 310. A detent means comprising the plunger 332 urged against the rod 330 by a spring 333 in a suitable bore 334 in the boss 319 engages in the notches 335 when proper shifted positions are selected. Indicating letters, D, and E, shown in Figure VI, are provided to show the position selected relative to the feeds and threads obtained as shown on the index plate 277. These positions are shown in column 336 of the index plate 277.

It can thus be seen from the above description that we have herein provided a feed box transmission of compact design and having a very wide range of feeds and threads which has a system of control levers simple and easy to operate and which are conveniently located for the operator in close association with the control means for the headstock. It is unnecessary for the operator to bend over in order to read the index plate or make the necessary manipulations of the control levers of the feed box as is an inherent defect in all prior constructions.

The driving power from the feed box 8 to the carriage control box 9 is transmitted through a 75

series of conveniently located change gears at the left hand end of the lathe. This drive comprises the helical change gear 337 which is removably mounted by suitable splined driving connection 328 and is securely held in place by the nut 339 threaded to the end of the output shaft 289. In Fig. VII, the standard change gear transmission from the feed box 8 to the carriage control box 9 would consist of the helical change gear 337 on the output shaft of the feed box 8 driving a helical idler gear removably mounted on the stud 341 adjustably secured to the quadrant 342, the idler gear in turn driving a gear of the same size and number of teeth as the gear 337 and removably mounted on the drive shaft 344 by means of the nut 345 in the same manner provided for mounting the gear 337. The quadrant is supported and clamped by suitable bolts 346 passing through elongated holes 347 in flanged portions 348 of the control box 9 so that various sized change gears can be applied to the feed box output shaft 289, the control box drive shaft 344, and the quadrant stud 341. The gearing just described is the standard arrangement utilized in operating the lathe in low back gear, high back gear, and high spindle speeds when it is desired to obtain the standard ranges of feeds and threads for use with these spindle speeds. When it is desired to obtain metric threads and feeds the usual metric transposing gear transmission may be substituted for the gearing described, the gears being made with helical teeth and of rela-

tively wide face to insure quiet running and long life. The wide faces also permit applying compound gears of normal width of face to the quadrant stud 341. Any desired odd feed and lead of thread may be obtained with this lathe by merely applying the proper gearing in place of these gears.

Having fully set forth and described our invention what we claim is:

In a change speed transmission, an input shaft, an output shaft, change speed gearing between said shafts comprising a pinion formed on said input shaft, a small gear fixed on said input shaft, and a large gear fixed on said shaft, a compound gear rotatably journaled on said input shaft, a gear rotatably journaled on said output shaft arranged to be in constant engagement with said pinion of the input shaft, a sleeve gear rotatably journaled on said output shaft and arranged in constant mesh with a gear of said compound gear journaled on said input shaft, a compound gear slidably mounted on said sleeve gear having its gears arranged to engage the small and large gears fixed on said input shaft and having clutching means for engaging the gear rotatably mounted on said output shaft, and a gear slidably mounted in driving relationship on the output shaft arranged to alternately engage a gear of said compound gear journaled on said input shaft and the sleeve gear journaled on said output shaft.
